Primary Examiner — Catherine S Posthauer(74) *Attorney, Agent, or Firm* — MH2 Technology Law Group, LLP(57) **CLAIM**

The ornamental design for an egg carton as shown and described.

DESCRIPTION

FIG. 1 is a frontal perspective view of the egg carton when the egg carton is in a closed configuration.

FIG. 2 is a rear perspective view of the egg carton seen in FIG. 1 when the egg carton is in an open configuration.

FIG. 3 is a front elevation view of the egg carton when the egg carton is in the closed configuration.

FIG. 4 is a rear elevation view of the egg carton when the egg carton is in the closed configuration.

FIG. 5 is a right side elevation view of the egg carton when the egg carton is in the closed configuration.

FIG. 6 is a bottom plan view of the egg carton when the egg carton is in the closed configuration; and,

FIG. 7 is a top plan view of the bottom portion of the egg carton when the egg carton is the closed configuration.

1 Claim, 4 Drawing Sheets(56)
